[57] CLAIM

The ornamental design of a handle for holding and remotely actuating an aerosol container, as shown and described.

DESCRIPTION

FIG. 1 is a left side view of a first embodiment of a handle for holding and remotely actuating an aerosol container according to the present design;
FIG. 2 is a right side view of said first embodiment;
FIG. 3 is a bottom view of said first embodiment;
FIG. 4 is a top view of said first embodiment;
FIG. 5 is a rear end view of said first embodiment;
FIG. 6 is a front end view of said first embodiment;
FIG. 7 is a left side perspective view of said first embodiment;

FIG. 8 is a left side view of a second embodiment of a handle for holding and remotely actuating an aerosol container according to the present design;
FIG. 9 is a right side view of said second embodiment;
FIG. 10 is a top view of said second embodiment;
FIG. 11 is a bottom view of said second embodiment;
FIG. 12 is a rear end view of said second embodiment;
FIG. 13 is a front end view of said second embodiment;
and,

FIG. 14 is a right side perspective view of said second embodiment.

The broken line showing of the aerosol container in FIG. 7 is for illustrative purposes only and forms no part of the claimed design.
